UNITED STATES PATENT OFFICE.

THOMAS A. BRIGGS, OF PROVIDENCE, RHODE ISLAND, ASSIGNOR TO BOSTON WIRE STITCHER COMPANY, OF PORTLAND, MAINE, A CORPORATION OF MAINE.

FASTENER OR STAPLE.

Original application filed December 15, 1924, Serial No. 755,932. Divided and this application filed May 18, 1927. Serial No. 192,281.

This application is a division of my prior application for patent, Serial Number 755,932, filed December 15, 1924.

The present invention relates to an improved form of fastener or staple for use in hand stapling machines and wire-stitching machines.

A principal object of the invention is to provide a fastener or staple which may be packaged in more compact form and handled more conveniently for packing and shipment and in the machine which applies the staples to the work.

Another object of the invention is to provide a form of fastener or staple which may be assembled in multiple in nested relation to conserve space and to maintain the staples in alinement to facilitate their delivery to the stapling-mechanism of the machine which applies them to the work.

The present improved form of fastener or staple is particularly adapted for use with the method of packaging staples and the improved package or cartridge shown and described in my prior application above referred to.

The invention is fully described in the following specification and illustrated by the accompanying drawings in which:

Fig. 1 is a perspective view of one form of my improved fastener or staple;

Fig. 2 is a similar view showing a slight modification in the form of the fastener or staple;

Fig. 3 is a perspective view of the staple package or cartridge, showing a portion of its side broken away to illustrate the manner in which the staples are held in nested relation therein;

Fig. 4 is a view of the staple after it has been bent into final shape, inserted through the work and its legs clinched against the under side thereof;

Fig. 5 is a perspective view showing one method of stacking or packing the staple-holders or cartridges; and

Fig. 6 is a perspective view showing another form of fastener or staple embodying the present improvement.

The present invention consists in general in providing as an article of manufacture and commerce a partly formed fastener or staple having its legs extending in divergent relation from its central head or cross-

bar to adapt a plurality of the staples to be 55 nested one within another with their legs in contiguous overlapping relation.

The staples may be packed and shipped in this form and applied to the stapling or wire-stitching machine in a package or cartridge to be fed to the driving- and setting-mechanism thereof, the stapling-mechanism acting to bend the legs of the staples into substantially parallel relation during the operation of applying them to the work. 60 65

As shown in Figs. 1 and 2, my improved fastener or staple may consist of a length of flat wire or a strip of sheet-metal having a straight cross-bar or head 2 with opposite legs 3 extending downwardly therefrom. 70 The usual form of staple of this type has its legs 3 projecting at right-angles to the head or cross-bar 2 and disposed in opposite parallel relation. In the present improved form of staple the legs 3, 3 project 75 in inclined relation to the head or cross-bar 2 and preferably they are disposed at an obtuse angle with respect to the under side of the head. In most cases the ends of the legs 3 of the staples are provided with sharp 80 points 4 which may be formed by cutting off the wire or strip at a sharp angle as shown in Fig. 1, while in other cases the ends of the legs are beveled or chamfered as shown in Fig. 2 to provide chisel points. 85

As described in my prior application above referred to, staples of the present form may be packaged for shipment and for use in the stapling or wire-stitching machines by assembling them in nested relation, as illustrated in Fig. 3 of the present drawings. In accordance with one feature of the invention disclosed in my prior application, the staples are arranged in contiguous nested relation along a strip of suitable 90 material, such as paper, fiber or metal and the edges of the strip are bent or folded to overlap the legs of the staples. The staples may be retained in the holder or container 95 5 of this form by crimping over the ends of the folded portions 6 as shown at 7 in Fig. 3. At the opposite end of the holder or contained 5 a detent ear or lug 8 is cut from the material and bent around to engage the endmost staple in the package. 100 105

As explained in my prior application from which this case is divided, the packages or cartridges of the form described provide

for greater convenience in packing the staples for shipment and in inserting a supply of the packaged staples as a charge for the machine. That is to say, the nested staples 5 may be used in a magazine on the machine, or a series of the packages or cartridges may be employed as a "clip" for furnishing a continuous supply of staples to the operating mechanism of the machine. The packages or cartridges may be disposed in inclined or vertical position as illustrated in Fig. 3 to deliver the staples from the bottom thereof in the manner of a chute or magazine; or a series of the packages or cartridges may be stacked as shown in Fig. 5 and the staples delivered successively from the ends thereof with the holders or containers ejected from the machine when emptied.

Fig. 6 illustrates a form of staple similar 20 to that shown in Fig. 1 except that it is constructed of round wire instead of flat wire or sheet stock.

In each instance the form of staple as herein illustrated adapts it for compact 25 packing and convenient arrangement for handling and feeding in the machine. As the staple is applied to the work its legs are bent down to stand at substantially right-angles to its cross-bar or head and in 30 parallel spaced apart relation to adapt the ends of the legs to be driven down through the work. After the legs of the staple are driven through the work, which may consist of several thicknesses of paper, card- 35 board or other material to be fastened together, the legs of the staple are bent over to clinch them against the under side of the work in the manner as shown in Fig. 4.

Heretofore in the art it has been the usual 40 practice to package fasteners or staples of the present type by arranging them in straddled relation along a wooden stick or a channeled strip of metal. Such a form of staple stick or holder has considerable bulk 45 and weight and cannot be packed compactly

for shipment. Furthermore, such staple sticks or holders of previously known form are awkward and unwieldly to handle in applying the staples to the machines in which they are used. With my present improved 50 form of fastener or staple a maximum number or quantity of the articles may be assembled and packed in a minimum space to facilitate handling and conserve space in 55 storing and shipping. Moreover, the nesting of the staples in the package or cartridge provides for maintaining them in proper alinement so that they may be fed to the mechanism of the machine which applies them to the work without chance of their 60 becoming misaligned or skewed out of position.

Having now described my invention, what I claim as new and desire to secure by Letters Patent of the United States is:

1. As a new article of manufacture, a wire staple having a head or cross-bar with legs at either end thereof initially bent to stand at obtuse angles with respect thereto to adapt the staple to be nested in contiguous relation with other staples of corresponding shape and to have its legs subsequently bent at substantially right-angles to its central cross-bar to project therefrom in parallel relation so that it may be driven into the work. 70

2. As a new article of commerce, a staple constructed from a length of wire initially bent to form opposite legs projecting at obtuse angles from the end of a central cross-bar whereby to provide for nesting it in contiguous relation with other staples of corresponding shape to form a compact package, said staple adapted to have its legs subsequently bent to stand at right-angles to its cross-bar and projecting therefrom in parallel relation whereby it may be driven into the work. 80

In testimony whereof I hereunto affix my signature.

THOMAS A. BRIGGS
